UNITED STATES PATENT OFFICE.

WALDO P. JOHNSON, OF CHICAGO, ILLINOIS.

COMBINATION REFRIGERATOR AND POULTRY CAR.

Application filed January 30, 1928. Serial No. 250,481.

This invention relates to improvements in combination refrigerator and poultry car and is shown in the accompanying drawings.

One of the features of my invention is the provision of a car adapted for carrying poultry, a part of said car being insulated for purposes to be hereinafter pointed out.

Among the features of my invention is the making of such a car with a poultry compartment at one end, a refrigerator compartment at the other end, and an attendant's state room in the center of the car between said compartments.

In the shipping of poultry it frequently is necessary or desirable to carry perishable feed or other products in the same car and keep the same cool to prevent spoiling. This can be accomplished by the use of my improved car. Also, at times, in hot weather it is necessary or desirable to cool the poultry. This can be accomplished by opening the doors from the refrigerator and poultry compartments leading into the state room and thus permit cold air to flow from the refrigerator compartment into the poultry compartment.

Also, sometimes in cold weather it is necessary or desirable to have a part of the car that can be kept warm. This can be accomplished by closing the door from the state room to the poultry compartment, opening the door between the state room and the refrigerator compartment and permit heat to flow from the state room into the refrigerator compartment.

Other features and advantages of my invention will appear more fully as I proceed with my specification.

In that form of device embodying the features of my invention shown in the accompanying drawings, Figure 1 is a horizontal sectional view, Fig. 2 is a view taken as indicated by the line 2 of Fig. 1, and Fig. 3 is a view taken as indicated by the line 3 of Fig. 2.

As shown in the drawings, the car is of the ordinary box car type in which, 10 indicates the floor and 11 the roof.

The car is divided primarily into three compartments as indicated by A, B, and C. A is the poultry compartment which may be of the usual arrangement with the center aisle 12 and tiers of poultry coops 13 on each side.

The state room B in the center of the car is preferably provided with a stove 14, and 15 and 16 indicate the sliding side doors of the car leading to the state room. 17 indicates a

door leading from the aisle 12 into the state room and 18 indicates another door leading from the state room B to the refrigerator compartment C.

The refrigerator compartment is provided with thick insulated walls 19 of any well known construction, and the door 18 is likewise insulated. One of the side walls 19 is provided with heavy insulated doors 19^a, as shown. The refrigerator compartment is also provided at one end with a suitable ice bunker 20 having a grating 21 near the bottom and a water drain 22 below. 23 and 24 indicate ports leading from the top and bottom respectively of the ice bunker to the main part of the compartment C to permit circulation of air for refrigeration purposes.

The top of the car is equipped with two funnel-shaped rotatable ventilators 25 and 26 respectively at the two ends as shown. The bottom of each of these ventilators is provided with a flange 26^a held beneath an overhanging collar 27 to permit rotation. One of these ventilators leads to the poultry compartment. It will be seen that by turning these ventilators in suitable directions air may be caused to circulate through the car as desired, depending upon the direction of the wind and movement of the car. For example, the doors 17 and 18 may be left open and the ventilators 25 and 26 adjusted so that the movement of the car will cause air to flow from the compartment C into the compartment A to cool the poultry.

While I have shown and described certain embodiments of my invention, it is to be understood that it is capable of many modifications. Changes, therefore, in the construction and arrangement may be made without departing from the spirit and scope of the invention disclosed in the appended claims, in which it is my intention to claim all novelty in my invention as broadly as possible in view of the prior art.

What I claim is new, and desire to secure by Letters Patent, is:

1. A railroad car of the box car type having a poultry compartment at one end with a central aisle having tiers of poultry coops on each side, a refrigerator compartment at the other end, and an attendant's state room between said compartments, doors leading from said attendant's state room to the poultry compartment and the refrigerator compartment, and means for causing flow of air from the refrigerator compartment through the

state room into the poultry compartment and vice versa, said means including a rotatable ventilator on top of the car.

2. A railroad car of the box car type having a poultry compartment at one end with a central aisle having tiers of poultry coops on each side, a refrigerator compartment at the other end, and an attendant's state room between said compartments, doors leading from 10 said attendant's state room to the poultry

compartment and the refrigerator compartment, and means for causing flow of air from the refrigerator compartment through the state room into the poultry compartment and vice versa, said means including rotatable 15 ventilators on top of the car at the ends thereof.

In witness whereof, I have hereunto set my hand this 26th day of January, 1928.

WALDO P. JOHNSON.
